ROLLING DOOR

Guy G. Mills, Columbus, Ohio

Application August 16, 1939, Serial No. 290,522

12 Claims. (Cl. 189—56)

The invention relates to an improved rolling door and particularly to a metal rolling door provided with connected sections of varying width which may be in the form of interengaging metal slats in combination with metal panels. The door may comprise metal panels exclusively, if desired, or a combination of interengaging panels and slats.

The principal object of the present invention is to provide a metal rolling door having sections of varying width; in a preferred form, relatively narrow engaging metal slats are employed in association with relatively wide panels which may be equipped with sash fitted with glass or other transparent or translucent material to allow transmission of light through the closed door; while the invention will be described with particular reference to a door, it will be understood that it is applicable generally to closures, including doors and windows although it is designed for particular employment in a vertical door comprising a plurality of interengaging horizontal superimposed sections which are raised and lowered in order to open or close the door.

Another object to provide a closure of the foregoing type wherein the door comprises a plurality of interconnected panels which may be equipped with windows and which are of successively increasing width towards the bottom of the door whereby they are adapted to be wound up on the winding drum in a compact arrangement with each successive layer on the drum concentric with the layer therebeneath.

Another object is to provide a door having interengaging slats at the top with panels therebelow, and to provide means on the panels whereby they will wind smoothly over the slats wound therebelow; in a preferred form means is also provided for insuring that succeeding slats or panels will be wound over the panels in a uniform concentric manner.

Another object is to provide in a rolling door windows having reinforcing sash and disposed in a staggered or overlapping fashion in adjacent panels whereby a door having maximum strength for a given light transmitting area is obtained.

Another object is to provide a rolling door having a drum which is offset for receiving the slats and for positioning the several layers of slats or panels or both in a true spiral whereby greater compactness is obtained together with a longer life of the door sections due to the greater freedom from stress as they are wound and unwound from the drum.

Still another object is to provide a polygonal

drum in association with a door which is composed of relatively wide sections adjacent the drum, the width of these sections being approximately equal to the width of the polygonal sections on the polygonal drum whereby smooth winding is obtained; in one form, the initially wound, relatively wide sections may be provided with means for insuring that subsequent relatively narrow sections are wound on an approximately circular form.

Still other objects will hereinafter appear.

In the accompanying drawings:

Figure 1 is a rear elevation of a door opening provided with one form of door embodying the principles of the present invention; in this figure, the door has relatively wide panels at the top and an interengaging slat curtain at the bottom.

Figure 2 is a vertical sectional view through Figure 1, showing the chain sheave for winding and unwinding the door.

Figure 3 is a view similar to Figure 1, but showing a door with relatively wide panels at the middle, these panels being equipped with staggered sash, and interengaging slat curtains at the top and bottom.

Figure 4 is a view similar to Figures 1 and 3 but showing a door made up of interengaging panels as distinguished from slats, the panels at the top of the door being relatively narrow in width, those adjacent the middle being wider and those at the bottom being still wider; these panels are so gauged in width that a succeeding group of sections will nest over a preceding group of sections.

Figure 5 is an end elevation partly in section of one form of drum and door, in which the winding drum is circular and the door has relatively wide panels adjacent its top, which panels are provided with concave segments for engagement with the winding drum.

Figure 6 is a vertical section through another form of drum and door, in which the panels are engaged with one another by a pinned hinge instead of by an interlocking hinge.

Figure 7 is a detailed rear elevation of a portion of the panel section of the door Fig. 6.

Figure 8 is an end elevation showing an offset winding drum of polygonal form on which is wound a door having panels at its top and a slat curtain therebelow, the panels being equipped with convex segments designed to form a drum so as to allow subsequent coiling of the slat curtain.

Figure 9 is a vertical section of a winding drum which is equipped with a door having a slat curtain at the top and a panel section therebelow,

the last slat being provided with an elevating lug connected to the first panel and designed to raise the end of the first slat to thereby permit subsequent smooth nesting of the panels over the 5 previously coiled slat curtain; the panels are provided with spaced convex and concave segments designed to permit smooth coiling of subsequent panels or slats.

Figure 10 is an enlarged end elevation of a 10 panel equipped on the inside with concave segments and on the outside with convex segments.

Figure 11 is an elevation of a panel equipped with segments at spaced intervals along its 15 length; this view shows that the segments designed to aid in nesting or coiling of the door are spaced at intervals horizontally along the panels.

Figure 12 is a horizontal section through one 20 end of a panel equipped with a sash and shows the details of arrangement of the panel and sash.

Figures 13 to 15 are detailed views showing 25 alternative methods of connection of a panel to a slat or to another panel.

Referring to the drawings in detail and, first, generally to Figures 1 to 4, reference numeral 1 designates a wall in which the door or closure 25 of the present invention may be located. Along the sides of the opening in wall 1 are provided a pair of vertical channels 2 which are adapted to guide the door in its vertical movement during 30 opening and closing. These channels 2 are secured in any desired manner to the sides of the opening. A winding drum housing 3 is mounted horizontally at the top of the door opening and is adapted to have the door wound and unwound 35 therein upon a winding drum 4 contained therewithin. Drum 4 is rotatably mounted about a stationary shaft 5, and is fixedly connected to a gear 6 in mesh with a pinion (not shown) driven by a toothed wheel 7 about which a chain 8 is 40 disposed whereby the door may be wound or unwound as desired by manipulation of chain 8. Preferably, a counterbalancing spring 9 is disposed within the winding drum, the spring having one end fastened securely to the winding drum 45 and the other end fastened securely to a collar 10 (see Figures 5 and 6) fixedly attached to stationary shaft 5. This spring is so disposed as to be placed under tension as the door is unwound to close the closure and to unwind during opening 50 of the door to thereby aid in the opening.

In Figure 1, there is shown a rolling steel door having at its top a panelled section made up of interengaging relatively wide panels 12 and at its bottom the usual interengaging slats 11. The 55 panels 12 are provided with sash designated generally as 13 which are disposed in non-overlapping relation in vertical rows. As indicated in Figure 12, these sash 13 comprise a pane of glass 17 faced on the front of the door with a reinforcing flat edge member 14 and on the rear with an angle edge member 15, members 14 and 15 being secured to the panel 12 in any desired manner and serving to reinforce or stiffen the same. Angle members 15 may be fixedly attached 60 to rearwardly extending upstanding flat members 16 attached to panel 12. If desired, panels 12 may not be equipped with sash. The sash may be fitted with other transparent or translucent material than glass to allow light to pass through 65 the closed door or window.

In Figure 3, there is shown an alternative construction wherein there is a slat portion made up of interengaging slats 11 at the top and bottom and wherein the central portion is made up 70 of panels 12, which may or may not be equipped

with sash 13. This figure shows a preferred arrangement of the sash 13 in which they are in overlapping position in different panels so as to provide the desired stiffness in the curtain as a whole, thereby making for a construction of maximum strength while of good light-transmitting character. The arrangement shown with the windowed panels in the center is particularly desirable for high windows or doors, allowing light to pass through at a level nearer the floor than where the windowed panels are in the top section of the door as in Figure 1.

Instead of the arrangements already described, the door may be provided with a slat curtain at the top and a panelled section at the bottom, 15 the panels being equipped or not with sash. This last construction is especially desirable for doors over eight feet in height which are operated by means of handles on the bottom of the door.

In Figure 4, there is shown an alternative construction wherein the door is made up exclusively of panels, those six in the top section designated 12a being of a first width and being adapted to form a first encircling layer around the drum, those six in the central section being designated 12b and being slightly wider so as to form a second encircling layer exactly conforming to the first layer on the drum and those of the bottom section 12c being still wider and likewise adapted to form a third encircling layer. The three uppermost panels 12a are hidden behind the drum housing and go up to and are attached to the drum. All of the panels in each group are of substantially the same width. By this construction, the initial section will coil over the drum which may be 30 polygonal (hexagonal) and the other two sections will be wide enough to rest successively over the first in close and perfect relationship thereto. Any or all of the panels may be fitted with sash. 35

At the bottom of each door in Figures 1, 3 and 4, a bottom slat or panel 18 is preferably provided which is adapted to engage the floor and which is not generally coiled onto the drum but merely pulled up into the drum housing. 40

In Figures 13 to 15, there are illustrated various 45 ways of securing interlocking between a panel and a slat or between adjacent panels. The panel 12 is provided where desired with a stiffener angle 19 adjacent its edge which serves to supplement or take the place of the reinforcing provided by 50 the sash 13. The panels 12 are of sufficient thickness and sufficiently reinforced to resist excessive bending under normal use or wind pressure. In Figure 13 the panel is provided at its 55 edge with a half slat 21 which is interlocked with an adjacent slat 11 to form a continuous hinge across the door. In Figure 14, the sheet metal panel 12 is rolled with an integral interlock 20 which interlocks with a similar extension on adjacent panels or on an adjacent slat 11. In 60 Figure 15, a pinned hinge is employed, the adjacent panels 12 being provided at their adjoining edges with half hinges 22 joined by a hinge pin 23. Various combinations of the several interlocking structures shown may be made as desired. 65

There will now be described the means whereby the coiling of a door of the foregoing type having sections of varying width upon the opening of the door is brought about. Various combinations of these are shown in Figures 5 to 11. 70

In Figure 5, the door has six relatively wide panels 12 adjacent its top, the uppermost panel being secured to the drum 4 by a lug, lugs or strap 24 riveted to the drum. At appropriate 75 horizontally spaced intervals along each panel 12

there are attached segments 25 which have a concave drum engaging surface 26. These segments 25 permit perfect nesting of the panel section on revolving metal pipe beam 4. The segments may be of metal or other suitable material which will bring about such nesting as shown. The succeeding slat curtain made up of slats 11 is adapted to be wound around the panel portion so nested. The result is an assembly which is compact and has increased life. The spacing of segments 25 along a panel is variable as desired and preferably a segment 25 is disposed at each end of a panel.

In Figure 6, there is shown a method of winding panels 12 which are provided with segments 27 having a concave drum-engaging surface 26 and pinned hinges 28, the first segments being attached to the drum 4 by a riveted lug 24 as in Figure 5. The sheet metal of panels 12 may be provided with an extension 29 overlapping a succeeding panel thereby presenting a tight joint when the door is lowered. Figure 7 is a rear view of a portion of a panel 12 of Figure 6, showing how the segments are riveted to the panel. Instead of riveting, bolts, welding or other mode of attachment may be employed.

Taking up Figure 8, there is illustrated a polygonal (hexagonal) winding drum 30 having flat sides 32 adapted to receive flatwise the panels 12 provided at the initial or top part of the door. These panels are provided with extending edge angles 19 which are adapted to be received in cylindrical recesses 31 in the drum 30. Recesses 31 allow the angles 19 to rotate therewithin and thus allow a succeeding panel 12 to pivot about its interlocking point thus allowing free seating and unseating during winding or unwinding. This view illustrates attachment of the first panel to the drum by means of a hinge 33 and an angle member 34 received in and secured to the drum, angle 34 being received in a recess which extends across the full length of the drum. The interlock hinge 33 may or may not be continuous and is preferably a strap hinge of any width required to properly carry the curtain weight.

In Figure 8, there is also shown the use of what I have chosen to call an offset drum 30 which is higher at 35 where the last of the last panel engages it than at 36 where the first of the first panel engages it by a distance such that the slat section which winds up next will continue to wind evenly. This offset feature may be used with any of the embodiments illustrated. The panels 12 are provided on their rear face with spaced segments 31 having convex outer faces 38 which form, in effect, a substantially circular drum upon which the slat curtain may coil thereby preventing the stress and unevenness brought about when winding the slat curtain upon the coiled panels of Figures 5 and 6, for example.

Figure 9 shows an initial curtain of slats 11 secured to the drum 4 by a lug, lugs or strap 48 and followed by a series of panels 12 which are provided on their inside with spaced segments 25 which have concave inner surfaces 26 and on their outside with spaced segments 37 having convex outer surfaces 38. The inner concave surfaces are adapted to closely engage the arcuate surface presented by either the drum 4 or the slats 11, as the case may be, while the convex outer surfaces are adapted to form a drum for succeeding layers of panels or slats. The last slat 11 is connected to the first panel by spaced elevating lugs or strap 39 which is adapted to be

fastened to the slat to which the panel is to be attached when panels are below the slat section of a door, to raise the point of connection between the slat and the first panel, thereby permitting subsequent smooth nesting of the panel upon the drum or previously coiled slats and preventing undue strain on the joint of interlock between the last slat and the first panel.

It is to be understood that various features of my invention may be combined with other features thereof without departing therefrom. For example, while the drawings show specifically certain features in combination with one another, the several features of the various views may be combined with features of other views. It is also to be understood that I intend to comprehend as within my invention such modifications thereof as may be necessary to adapt it to varying conditions and uses and as fall within the scope of the appended claims. Thus, the panels or sections of the door may continuously increase in width from top to bottom, each panel being slightly wider than the preceding one.

In the claims by the term "substantially flat" I mean panels which are flat as compared with the curvature of the drum or of the preceding sections of the door wound on the drum.

Having thus fully described my invention, what I claim as new and desire to secure by Letters Patent is:

1. In combination, in a rolling door, a winding drum, an articulated rolling door adapted to be wound upon said drum, said door comprising a plurality of substantially flat relatively wide interlocked sections, and a plurality of horizontally spaced means attached to the inward face of said sections, said means being concave on their inward surfaces for engaging the convex surface of the drum or of a preceding section of the door wound thereon.

2. In combination, in a rolling door, a winding drum, an articulated rolling door adapted to be wound thereupon and comprising a plurality of substantially flat relatively wide interlocked sections, and a plurality of horizontally spaced means on the outer faces of said sections for presenting a convex surface to succeeding sections of the door wound thereover.

3. In combination, in a rolling door, a winding drum, an articulated rolling door adapted to be wound thereupon and comprising a plurality of substantially flat relatively wide interlocked sections, a plurality of horizontally spaced means on the inner faces of said sections for presenting a concave surface to the drum or to preceding sections of the door wound thereupon, and a plurality of horizontally spaced means on the outer faces of said sections for presenting a convex surface to succeeding sections of the door which are wound thereover.

4. In combination, in a rolling door, a circular winding drum, a rolling door adapted to be wound thereupon and comprising a plurality of interlocked sections, and means for elevating the edge of one of said sections as it is wound upon the drum, said elevating means comprising a member extending inwardly from said edge and adapted to support said edge away from the drum or the surface of preceding wound sections of the door and for thereby insuring even coiling thereof upon the drum.

5. In combination, in a rolling door, a winding drum, a rolling door adapted to be wound thereupon and comprising a plurality of interlocked

- sections comprising a group of adjacent relatively broad substantially flat sections and a succeeding group of adjacent relatively narrow sections, and means carried by said relatively broad sections on the outer faces thereof for forming a substantially circular drum-like surface for said relatively narrow sections as said door is wound upon said drum.
6. In combination, in a rolling door, a circular winding drum, a rolling door adapted to be wound thereupon and comprising a plurality of interlocked sections comprising a group of adjacent relatively broad substantially flat sections and a succeeding group of adjacent relatively narrow sections, means carried by said relatively broad sections on the inner faces thereof for presenting a concave surface to the drum or to underlying sections of the door wound upon the drum, and means carried by said relatively broad sections on the outer faces thereof for presenting exteriorly a convex drum-like surface upon which said relatively narrow sections may be wound.
7. In combination, a winding drum, a rolling door adapted to be wound thereupon and comprising a plurality of interlocked sections comprising a group of adjacent relatively broad sections, said winding drum having a polygonal cross section, said relatively broad sections being adapted to be wound upon said drum in a position parallel to the polygonal surface thereof and means on the outer surface of said relatively broad sections for presenting a convex drum-like surface for succeeding sections of said door wound thereover.
8. In combination, a winding drum, a rolling door adapted to be wound thereupon and comprising a plurality of interlocked sections comprising a group of adjacent relatively broad sections, said winding drum having a polygonal cross section, said relatively broad sections being adapted to be wound upon said drum in a position parallel to the polygonal surface thereof, and means on the outer surface of said relatively broad sections for presenting a convex drum-like surface for succeeding sections of said door wound thereover, said drum being of such configuration that the convex drum-like surface formed by said last named means assumes a spiral from the point of attachment of the door to the drum around the drum to a point adjacent said point of attachment and outwardly thereof whereby bulging of succeeding sections of the door as they pass said point of attachment is prevented.
9. A closure comprising a circular winding drum, an articulated rolling door mounted thereon and comprising a group of adjacent relatively
- ly wide substantially flat panels, and a succeeding group of articulated narrow slats, a plurality of horizontally spaced segments mounted on the inner faces of said panels and having a concave inner face adapted to engage the outer surface of said drum or of sections of said door wound thereupon, and a plurality of horizontally spaced segments mounted on the outer faces of said panels and having a convex outer surface adapted to be engaged by succeeding sections of said door, said last-named segments which are peripherally successive cooperating to form an approximately cylindrical surface upon which succeeding sections of said door may be wound.
10. A closure comprising a circular winding drum, an articulated rolling door mounted thereon and comprising a group of adjacent relatively wide substantially flat panels and a succeeding group of articulated narrow slats, a plurality of light-transmitting sash in said panels, a plurality of horizontally spaced segments mounted on the inner faces of said panels and having a concave inner surface adapted to engage the outer surface of said drum or of sections of said door wound thereupon, and a plurality of horizontally spaced segments mounted on the outer faces of said panels and having a convex outer surface adapted to be engaged by succeeding sections of said door, the peripherally successive last-named segments cooperating to form an approximately cylindrical surface upon which succeeding sections of said door may be wound.
11. A closure comprising a circular winding drum, an articulated rolling door mounted thereon and comprising a group of adjacent relatively wide substantially flat panels, a plurality of light-transmitting sash in said panels, said sash having reinforcing edge members acting to reinforce said panels, and a plurality of horizontally spaced segments mounted on the inner faces of said panels and having a concave inner face adapted to engage the outer surface of said drum or of preceding sections of said door wound thereupon.
12. A closure comprising a circular winding drum, an articulated rolling door mounted thereon and comprising a group of adjacent relatively wide substantially flat panels, a plurality of light-transmitting sash mounted in said panels in staggered relationship in adjacent panels, said sash having reinforcing edge members around them acting to reinforce said panels, and a plurality of horizontally spaced segments mounted on the inner faces of said panels and having a concave inner face adapted to engage the outer surface of said drum or of preceding sections of said door wound thereupon.

GUY G. MILLS.
